ALBERT G. MANNS, OF OCONOMOWOC, WISCONSIN, ASSIGNOR TO ALBERT O. TROSTEL,
OF MILWAUKEE, WISCONSIN.

METHOD OF EMBOSSED LEATHER.

Application filed May 3, 1926. Serial No. 106,514.

The invention relates to a method of embossing leather, oilcloth, imitation leather, and similar materials.

The usual method of embossing leather 5 consists in subjecting the leather to the action of a rigid die in which the pattern or design has been cut. These dies are very expensive and on the average two out of three of such dies have to be scrapped be-
cause the designs do not take with the public. Furthermore, these dies are in the form of plates which are of limited size and hence require a constant shifting of the die relative to the material to be embossed, with the at-
tendant disadvantage of being unable to make a continuous design over the entire surface, as it is impossible to match separate impressions made by the die and hence the leather or other material does not have the pattern impressed thereon in one continuous sequence throughout the entire material.

I have found that the usual rigid cut dies, with their great expense and disadvantages, may be dispensed with in embossing designs 25 on leather, including patent leather or materials having a patent leather finish, such as imitation leather and oilcloth, by using dies of woven material, such as woven wire, or fabrics, such as lace. Such dies may be readily and cheaply obtained, in continuous 30 patterns of any length desired, and the scrapping of one design or pattern for another more popular design entails a negligible loss.

35 The invention further consists in the several features hereinafter set forth and more particularly defined by a claim at the conclusion hereof.

In the drawings Fig. 1 is an elevation view 40 of apparatus used in connection with the process;

Fig. 2 is a plan view showing progressively the finished embossed material or leather with the die superimposed thereon and the 45 die.

Referring to Fig. 1, the numeral 3 designates the level bed of a press, 4 a movable pressing platen, 5 a flexible die and 6 the leather or material to be embossed.

50 In practising the process, the leather or other material above mentioned may be placed upon the bed 3 of the machine, with the finished side up, and the flexible die is either placed over the finished side of the leather, so as to be acted upon by the platen

5, or is secured to move with said platen, or the flexible die may be placed upon the bed, the finished side of the material superimposed upon this flexible die, and the platen act on the other side of the material. In other words, the die 5 is forced into the finished face of the leather or other material and leaves thereon the impression of its design as said die and the leather are pressed together between the bed 3 and the platen 4, and upon removing the die the design of the die material will be found to be impressed upon the leather.

It is to be noted that instead of using a pressing platen having a small reciprocating head that the pressing platen may be in the form of a roller that travels over the material and relative to the bed throughout its pressing operation, but as the invention herein relates to the process and not to any particular form of apparatus, further description thereof is deemed unnecessary.

The material forming the die may be of woven wire, or fabric, more particularly lace, whose delicate tracery will be embossed upon the leather, as shown at 7 in Fig. 2, adjacent the heavier portion at 8, showing the leather with the die superimposed thereon. That portion of the pressing apparatus which is disposed next to the die is preferably heated 85 to a suitable temperature, as for instance 200° F., so as to facilitate the impression of the design upon the material.

As the cost of laces or other suitable die material is infinitesimal compared to the cost 90 of the heavy cut steel plate dies usually employed, the shifting from one design to another in factory production is an easy matter, and the facility with which a continuous pattern may be embossed upon a whole side of leather or upon a great length 95 of material, such as imitation leather and oilcloth, which have a finish similar to patent leather, and the available selection of die material being myriad, a greater variety of 100 designs may be put out more expeditiously and at less cost than with the former rigid die process, and with a resulting increase in demand because of the greater number of 105 pleasing patterns to choose from, and the reduced cost of the material.

While the invention herein has been more specifically described in connection with leather and the process may be used on leather finished or unfinished, and on patent 110

leather, and may also be used on materials with linseed oil or pyroxylin finish. I desire it to be understood that the invention is not to be limited unless specifically specified to its use on leather, and also that by the term "patent leather", used in this specification and claim, I mean a leather finished with a linseed oil coating or a pyroxylin coating.

What I claim as my invention is:

- 10 The process of embossing designs upon

patent leather or other materials having a patent leather finish, which consists in subjecting the material to heat and pressure while in contact, on its finished side, with lace to indent said finish in the form of the design of the lace.

In testimony whereof, I affix my signature.

ALBERT G. MANNS.
